UNITED STATES PATENT OFFICE.

DANIEL KOPS, OF NEW YORK, N. Y., ASSIGNOR TO KOPS BROTHERS, INC., OF NEW YORK, N. Y., A CORPORATION OF NEW YORK.

APPAREL CORSET.

Application filed February 8, 1922. Serial No. 534,353.

To all whom it may concern:

Be it known that I, DANIEL KOPS, a citizen of the United States, residing in the borough of Manhattan, city, county, and

5 State of New York, have invented an Improvement in Apparel Corsets, of which the following is a specification.

This invention relates to an apparel corset and more particularly to that type of 10 garment known as "Nemo" Marvelace corset, in which there are devices for adjusting the garment to position on the body of the wearer. Furthermore, the present invention relates to that type of garment as 15 shown and described in my copending application, Serial No. 512,990, filed November 5, 1921, and is another form of the same.

The tendency in accordance with prevailing fashion is to produce the appearance 20 of an uncorseted or natural figure and in this type of garment the structure is such as to produce this result and at the same time provide means for adjustment and necessary support where the same is required 25 for the abdominal portions of the body of the wearer. In carrying out the present invention, therefore, the garment which is preferably a closed back corset is constructed with the front members made of 30 similar parts each comprising a front steel section, a section of yielding fabric or other material between the front steel section and the adjacent portion of the body of the garment, the yielding section also extending 35 from the upper to the lower edge of the garment, together with adjusting tension and supporting devices extending from approximately the waistline to approximately the 40 groin line of the wearer and so embodied in the garment as to be readily adjusted to position. In this type of garment the support of the abdomen of the wearer is effected without the use of the usual supporting straps or flaps and the upper portion 45 of the garment is free to permit the body to assume its natural position at the same time affording the same more or less support while the same conditions maintain with those portions of the body below the

groin section which are covered by the garment, as will be hereinafter more particularly described.

In the drawing:

Fig. 1 is a perspective view illustrating the corset made in accordance with my present invention, and

Fig. 2 is an elevation on an enlarged scale showing the front inner portion of the garment.

The garment made to include the present 60 invention is preferably one in which the adjusting devices are entirely in the front sections of the corset and the back of the garment is closed, although as will be understood the improvement to which the present 65 invention relates may in some instances be applied to a corset made in the customary halves. In the present instance the front portions of the garment are similarly constructed and for this reason but one of these 70 will be specifically described. Referring to the drawing in the front of the corset I employ the customary front steel sections indicated at 10 and 11. These are provided with the necessary connecting clasps including a series of studs 12 attached to one steel 75 and a corresponding series of sockets 13 attached to the other steel. Each front steel section is also preferably provided with a downward extension. That of the front 80 steel section 10 is indicated at 14, while that of the front steel section 11 is indicated at 15. These extensions 14 and 15 may be provided with rows of eyelets 16 and 17 respectively through which laces 18 are passed 85 for connecting and adjusting the lower front portions of the garment to one another. Also as indicated these extensions 14 and 15 immediately below the ends of the 90 steels may be fitted with a clasp, the hook member of which is designated at 19.

In each front portion of the corset I employ an elastic section indicated at 20 preferably made of suitable elastic fabric, although the material of which this section is 95 made forms no part of the present invention. Furthermore, as illustrated, the yielding section 20 may be constructed of mem-

bers of different elasticity, the top member 21, the bottom member 22 and the central member 23 each being composed of material having any desired degree of elasticity. 5 These members also, when the section is made of divided parts, may be suitably connected along adjacent edges. For example as illustrated in Fig. 2, the adjacent edges of the parts 21 and 23 are connected along 10 a line of stitching 24 and similarly the parts 22 and 23 are connected along the line of stitching 25. This yielding section extends from the top to the bottom of the garment and at one edge is secured to the front steel 15 section by a line of stitching indicated at 26, while at the opposite edge it is secured to the adjacent portion of the body of the garment along a line of stitching indicated at 27, this line of stitching preferably forming part of a stay pocket which is at the 20 forward edge of the body 28 of the garment. I also employ an adjusting strap 29 which at one edge is secured to the front steel section by the line of stitching 26 which, as 25 hereinbefore stated, also connects the front steel section to the yielding fabric member. At the opposite edge of this adjusting strap there is a series of eyelets 30 in suitably spaced positions. Associated with the 30 adjusting strap there is an anchor strap 31. Along one edge this anchor strap is secured to the adjacent portion of the body of the garment by the line of stitching 27 which also secures the corresponding edge of the 35 yielding fabric member thereto. In the anchor strap 31 is a series of eyelets 32 corresponding in number with the eyelets 30 in the adjusting strap. A lace 33 is threaded through the eyelets 30 and 32, and also when 40 the adjusting strap and the anchor strap are on the inner side of the garment the lace 33 is threaded through eyelets 34 so as to make it possible to effect the lacing adjustment from the outer side of the garment 45 after the same is in position on the body of the wearer. As indicated the adjusting strap and the coacting anchor strap are on the inner side of the garment and are preferably made of inelastic material. The upper edges 50 of these members extend downwardly while the lower edges extend upwardly, but it will be understood that these parts may have different configurations without departing from the nature of the invention. 55 Also as illustrated I may employ the usual hose supporters, one of which is indicated at 35 and is attached to and extends downwardly from the lower end of the extension of each front steel section and another indicated at 36 extends from the forward end 60 of the lower edge of the skirt 37. It will now be understood that in the use of the apparel corset hereinbefore described the adjustment of the garment to place on 65 the body is readily effected exteriorly of the

corset to provide the required support in necessary cases for the abdominal portion of the body, at the same time permitting those portions of the body both above the waistline and below the groin section to assume a 70 natural position and to thus produce the desired uncorseted or natural appearance.

I claim as my invention:

1. In an apparel corset and in each front portion thereof, a front steel section, an elastic section between the front steel section and the adjacent portion of the body of the garment extending from the upper to the lower parts thereof, and adjustable inelastic supporting devices on the inner side of the 80 garment extending substantially from the waistline to the groin section. 75

2. In an apparel corset and in each front portion thereof, a front steel section, an elastic fabric section between the front steel section and the adjacent portion of the body of the garment extending from the upper to the lower edges thereof, and adjustable inelastic supporting devices coextensive circumferentially with the elastic fabric section 90 and extending substantially from the waistline to the groin section on the inner side of the garment. 85

3. In an apparel corset and in each front portion thereof, a front steel section, an elastic fabric section between the front steel section and the adjacent portion of the body of the garment extending from the upper to the lower edges thereof, an inelastic supporting device underlying the elastic fabric section 95 and extending from approximately the waistline to the groin section of the garment, and means for adjusting said supporting device to position exteriorly of the 100 garment. 105

4. In an apparel corset and in each front portion thereof, a front steel section, an elastic fabric section extending between the front steel section and the adjacent portion of the body of the garment and also from the top to the bottom edges thereof, an elastic strap secured along one edge to the front steel section, an inelastic strap secured along one edge to the forward section of the body of the garment, the said straps extending 110 from approximately the waistline to the groin section on the inner side of the garment, and means for adjusting the relative positions of the said straps to secure the garment in position on the body of the 115 wearer. 120

5. In an apparel corset and in each front portion thereof, a front steel section, an elastic fabric section extending between the front steel section and the adjacent portion 125 of the body of the garment and also from the top to the bottom edges thereof, an inelastic strap secured along one edge to the front steel section at one edge of the said elastic fabric section, an inelastic strap secured along 130

one edge to the forward section of the body of the garment at the opposite edge of the said elastic fabric section, the said straps extending from approximately the waistline 5 to the groin section of the garment, and a lace threaded through the adjacent edges of the said straps and passing to the outer

side of the garment for adjusting the said straps relatively to position in adjusting the garment on the body of the wearer. 10

Signed by me this 16th day of January, 1922.

DANIEL KOPS.
